FIG. 2.

FIG. 1.

FIG. 3.

FIG. 5.

By His Attorney

-17-f Inventor
Abraham Rodow

Israel Benjamins.

UNITED STATES PATENT OFFICE.

ABRAHAM RODOW, OF NEW YORK, N. Y.

WINDOW-CLEANING DEVICE.

1,283,914.

Specification of Letters Patent.

Patented Nov. 5, 1918.

Application filed May 18, 1918. Serial No. 235,332.

To all whom it may concern:

Be it known that I, ABRAHAM Rodow, a citizen of the United States, residing at New York, in the county of Bronx and State of New York, have invented a new and useful 5 Window-Cleaning Device, of which the following is a specification.

My invention relates to improvements in a device for cleaning the panes of window 10 sashes, which are adapted to slide vertically between suitable weather strips, and it consists in the novel features hereinafter more fully described.

The objects of my improvement are:

15 First: To provide a means whereby the outer side of window panes may be effectively cleaned by a person located inside of the room, without leaning out of the window.

20 Second: To have said window cleaning means readily applicable to windows of various sizes, and

Third: To have said means simple, durable and inexpensive.

25 I attain these objects by the device illustrated in the accompanying drawings or by any mechanical equivalent or obvious modification of the same.

In the drawings Figure 1 is a vertical section on the line E—F of Fig. 5; Fig. 2 is a vertical section on the line C—D of Fig. 4, looking toward the left; Fig. 3 is a vertical section on the line C—D of Fig. 4 looking toward the right; Fig. 4 is a plan or 35 top view of my window cleaning device, and Fig. 5 is a horizontal section on the line A—B of Fig. 1.

Similar numerals and letters refer to similar parts throughout the several views.

40 11 is one of the two vertical hollow legs of a U-shaped member, 11^a is the other hollow leg, and 18 is the curved hollow branch connecting said legs 11 and 11^a.

The leg 11 has a slot 12 on the right side 45 thereof and the leg 11^a has a slot 13 on the right side thereof.

15 and 14 are reinforcements for said legs 11 and 11^a respectively which reinforcements are shown as hollow in the drawings, but 50 which may also be solid, if desired, and they may have any convenient shape.

Said legs 11 and 11^a and said reinforcements 15 and 14 are shown in Fig. 1 as 55 plugged up at their upper ends by the stop pieces 22, 20, 21 and 19 respectively.

16 is a flexible strip of metal shown as inclosed by said legs 11, 11^a and branch 18; said strip 16 has connected thereto at one end thereof the handle 33, which is secured thereto by means of screws 32 passing 60 through said slot 12 and adapted to be moved therealong.

The washers 31 are interposed between said strip 16 and the front wall of said leg 11 inside thereof to prevent the jamming of 65 said strip 16 against said front wall.

By means of said handle 33 said strip 70 may have a reciprocating motion imparted thereto inside of said U-shaped member 11—18—11^a.

To the other end of said strip 16 is secured the carrier plate 24 and the middle portion of a plate spring 26 by means of the set screw 26^a; the washer 26^b is employed for properly spacing said strip 16 from the 75 front wall of said leg 11^a.

Said carrier plate 24 is provided with rollers 24^b, which are shown as placed in contact with the front wall of said leg 11^a, to facilitate the motion of said carrier plate 80 thereon, and the lugs 24^a adapted to slide between the guides 25, which are shown as made in one with the box 27, which is secured to the plate 28, hereinafter described. Said box 27 incloses the ends of said spring 85 26, which are bent over at an angle of 180 degrees and secured to the back wall of said box 27 inside thereof.

The plate 28 has a depression on the right side thereof, which is shown as filled with a 90 pad of cotton 29 or any other fibrous material, and a mop 30 may be secured over the edges of said plate 28 and on the face of said pad 29 in contact with the glass pane 34 of the window sash 35.

95 It is evident that said U-shaped member 11—18—11^a may be slipped over any window sash or pair of window sashes by a person situated inside of the room, and have the plate 28 with the pad 29 and mop 30 brought 100 into contact with the exterior side of the pane 34, and by moving said handle 33 up and down, to have said exterior side of said pane effectively cleaned without having to lean out of the window. Said spring 26 105 serves to press said plate 28 with said mop 30 against said pane 34, and to permit the passage of said plate 28 over any sash or sashes 35.

Many changes could be made in my win- 110

dow cleaning device and in the details thereof without departing from the main scope of my invention.

I do not therefore restrict myself to the 5 details as shown in the drawings, but I intend to include also all mechanical equivalents and reasonably obvious modifications thereof.

What I claim as my invention, and desire 10 to secure by Letters Patent is:

1. A window cleaning device comprising a hollow U-shaped member, a flexible strip inclosed by said member and adapted to be moved therein, a slot in each of the two legs 15 of said member, a handle connected to said strip at one end thereof by means passing through the slot in one of said legs and adapted to move therein, a carrier plate connected to said strip at the other end thereof by means passing through the slot in the other of said legs and adapted to move therein, a cleaning plate adapted to be applied for cleaning the panes of window sashes, a spring connecting said cleaning 20 plate to said carrier plate, rollers situated in grooves in said carrier plate in contact with said other leg and guides for said carrier plate connected to said cleaning plate.

2. A window cleaning device comprising a 25 hollow U-shaped member, a flexible strip inclosed by said member and adapted to be

moved therein, a slot in each of the legs of said member, a means for moving said strip connected at one end thereof by means passing through the slot in one of said legs and 35 adapted to move therein, a carrier plate connected to said strip at the other end thereof by means passing through the slot in the other of said legs and adapted to move therein, a cleaning plate for window panes, a spring, connecting said cleaning plate to 40 said carrier plate and guides for said carrier plate secured to said cleaning plate.

3. A window cleaning device comprising a hollow U-shaped member, a flexible strip 45 inclosed by said member and adapted to be moved therein, a slot in each of the legs of said member, a means for moving said strip, connected at one end thereof by means passing through the slot in one of said legs and 50 adapted to move therein, and a cleaning plate extensibly connected to the other end of said strip and adapted to move therewith lengthwise of said other leg.

4. A window cleaning device comprising 55 a U-shaped member, a flexible means adapted to have its ends move lengthwise of said member, a means for moving said flexible means, connected at one end thereof, and a cleaning plate extensibly connected to the 60 other end thereof.

ABRAHAM RODOW.
